AUTOMATIC SAFETY RAZOR

Oscar R. Peterson, Brooklyn, N. Y.

Application February 9, 1931. Serial No. 514,554

4 Claims. (Cl. 30—12)

This invention relates to safety razors of the reciprocating type, and more particularly to that class in which a reciprocable blade assembly unit is caused to reciprocate by means of a roller mounted on the razor.

The main object of my invention is to provide a safety razor which possesses the advantages of the known varieties, but which in addition has the highly useful feature of a blade which reciprocates automatically during use, whereby the cutting efficiency is greatly enhanced and the entire edge of the blade comes constantly into play.

Another object is to provide such a razor with a blade assembly unit which may be readily removed for blade renewals.

A further object is to have a razor of the class indicated which is entirely automatic in use by virtue of a roller thereon which readily makes contact with the skin in use and which by its resulting rotation propels the blade in reciprocating movement.

Yet another object is to have an automatic safety razor of this class whose automatic operation may be resorted to or avoided at will without the least inconvenience and without in any way necessitating any alteration or change in the razor as a whole.

Above all, it is an object of the invention to provide a razor with an automatic feature which is so unobtrusive and simple in construction that it cannot get out of order and will in no way detract from the razor when said automatic feature is intentionally ignored while using the razor.

Other objects and the various advantages inherent in my invention will appear more fully in detail as this specification proceeds.

In the accompanying drawings forming part hereof

Fig. 1 is a perspective view of a safety razor made according to the main principles of my invention and embodying all the advantages and desirable features thereof.

Fig. 2 is a view of the same razor when used for shaving, and illustrates the automatic feature as being in full operation.

Fig. 3 is a top plan view of the same razor with the blade assembly unit in middle position.

Fig. 4 is a side view of the razor when the blade assembly unit is in its extreme right position.

Fig. 5 is a similar view with the same blade unit in extreme left position.

Fig. 6 is a perspective view of the main frame of the razor when the bridge is in open position and the blade assembly unit has been removed.

Fig. 7 is a side view of the blade assembly unit mentioned.

Fig. 8 is an end view of the same unit.

Fig. 9 is an end view of the cap member of the same unit.

Throughout the views, the same reference numerals indicate the same or duplicate parts.

It is a well known fact that in razors, the blades thereof cut the hairs during shaving solely by virtue of the keen character of the edges doing the cutting, as said edges engage the hairs directly head-on. Attempts have been made to increase the cutting capacity by setting such blades diagonally and tilting them at various angles. It is, on the other hand the conclusion of actual test and experience that side motions or reciprocation of such blades will immediately enhance their efficiency and increase their capacity.

With this fact in mind, the present invention has been designed, with various features and refinements super-added, as already indicated to a certain extent.

In the practice of my invention a handle 2 has a gap frame 3 surmounted by a pair of rails 4, 4 which are connected at one end by a cross member or rigid bridge 5. To this cross member 5 is hinged a swingable bridge 6 at 16, whose purpose will presently appear.

The rails 4, 4 are provided at their outer edges with rows of teeth 11, 11 which serve as guards for a razor blade 8. The latter blade is held in assembly with a cap member 7 which has a pair of guide studs 15, 15 to locate the blade by means of a retaining member or bar 19, while a nut 20 is screwed on threaded stud 22 and retains the parts in a unit. This blade assembly unit just described is slid in over rails 4, 4 of the main frame of the razor and is retained slidably above the same upon a pair of undercut or dovetail gibs 10, 10. The blade is curved concavely to conform with the curved underside 23 of cap member 7 and rides directly on the gibs which in effect are the true rails here, while the side edges 21, 21 of retaining member 19 of the blade assembly are dovetailed to correspond with the gibs. The unit may thus slide back and forth along the gibs the same as the guards 11, 11 being made longer than the blade to allow such movement.

The open end of the main frame between rails 4, 4 are preferably closed to prevent the blade unit from sliding off, and this is one function of the swingable bridge 6 previously mentioned.

This bridge 6 has a pair of converging finger pieces 9, 9 bent down at the free end of the bridge and arranged to fit hard between the ends of the rails 4, 4. Upon the finger pieces are formed a pair of corresponding notches 18, 18 which allow the finger pieces to spring apart somewhat when said notches engage the rails, this having as the desired effect that the bridge is locked in closed position upon the frame when it has been swung down and snapped into position. The finger pieces together form a barrier or retaining end of bridge 6 for the blade unit

at one end, while the hinge end 16 of the bridge forms a stop at the other end, thus completely preventing loss of said unit while permitting it to shuttle back and forth on the frame from end 5 to end.

However, in order to provide for positive shutting or reciprocation of the blade unit, a roller 12, preferably knurled is rotatably mounted between a pair of lugs 13, 13 on bridge 6 and is further provided with a cam slot or groove 14 entirely surrounding the same. Corresponding with this groove, a projection 17 on cap member 7 of the blade unit is arranged to project into the groove of the roller. The groove is cut diagonally from right to left about half the circumference of the roller, and back again from left to right about the remaining half, as especially contrasted in Figs. 4 and 5. If now, by any means the roller is rotated owing to the nature of the slot, the projection which rides in it will be forced to shift, first in one direction, and then back in the opposite direction and so on, so long as rotation of the roller continues. The blade shifts rapidly from the position at its extreme left shown in Figs. 1 and 5 through an intermediate position indicated by Fig. 3 to extreme right position as shown in Fig. 4 after which it returns again to the left, etc.

It is preferred to cause rotation of the roller by allowing the same during shaving to come into direct contact with the skin of the face 1 for example, simultaneously with contact of one guard 11 and one edge of blade 8. The mere act of drawing the razor downward upon the face will cause the roller to rotate by traction upon the skin, and this, of course, immediately reciprocates the blade very materially increasing the effect of the edge of the blade.

If it is not desired to use the roller and its blade reciprocating effect, the razor need but be tilted slightly so that the roller no longer touches the face, and a straight, ordinary shave is had, the roller and its supporting bridge 6 in no way affecting the use of the razor. In such a case, the blade can be shifted to an extreme right position by turning the roller slightly with the finger, the position of Fig. 4 and the blade used on both edges until dull. Then the blade can be shifted to the extreme left position the position of Figs. 1 and 5 when the portions of the edges hitherto obstructed and protected by the individual teeth of the guards will be exposed for use, and both edges will be as though renewed.

When it is desired to remove the blade assembly unit for blade renewals the bridge 6 may be readily released and opened by holding the razor handle 2 in one hand while pinching finger pieces 9, 9 with the thumb and index finger of the other hand. Owing to converging form of the outer edges of the finger pieces, the finger piece notches 18, 18 are not merely released from engagement with rails 4, 4 but the finger pieces tend to slip upward from the fingers when thus released, and the whole bridge springs suddenly out of the fingers and swings to a position similar to that shown in Fig. 6. The blade unit may, of course, then be slid out and tended to separately.

The projection 17 on cap member 7 may be integral therewith or not and may be altered into a plurality of projections and a corresponding number of similar grooves made in the roller. Other modifications which are obvious to those

skilled in the art could also be made within the scope of my invention, and such I reserve.

Having now fully described my invention, I claim:-

1. In an automatic safety razor having a frame 80 including a pair of spaced guards connected at one end by a cross piece, a hinge member integrally formed with said cross piece, a bridge hinged to said hinge member and provided with a bifurcated extremity adapted to be swung down 85 between the ends of said guards distant from the cross piece within the outline of the frame as a whole, said bifurcations being exteriorly notched to engage said guards in locking engagement and converged to form resilient finger pieces which 90 tend to slip upward out of the fingers, whereby said bifurcations may be released from said guards and simultaneously propelled upward to automatically open said bridge in positive manner, there being blade carrying means supported 95 between said guards beneath said bridge.

2. In an automatic safety razor having a pair of spaced guards surmounting a handle and a blade assembly supported between said guards and reciprocable therebetween, one of said guards 100 being removably attached to the other at one end thereof, the combination, with a cap plate associated with said blade assembly and a cam roller supported above said cap plate on the removable guard of said pair of guards of a 105 very obtuse integral projection upon said cap plate beneath said cam roller and a correspondingly wide angled and open concave cam portion in said cam roller normally engaging said obtuse projection, in order to tend to shift said 110 blade assembly in the direction of its reciprocating movement with respect to said cam roller and properly register said cam portion with said cap plate projection when placing the blade assembly in commission for operation after replacing said assembly and upon attaching said removable guard to the other guard of said pair of guards.

3. A safety razor having a guard, and blade supporting means in combination with a bridge 120 member hinged at one end of said guard and comprising a bifurcated extremity adapted to be swung down between projections at the opposite end of said guard from that at which said bridge is hinged, said bifurcations being exteriorly 125 notched to engage said projections in locking engagement and extended to form resilient finger pieces which tend to slip out of the fingers whereby said bifurcations may be released from locking engagement and propelled away, there being 130 blade means supported by said blade supporting means between said guard and said bridge.

4. A safety razor which comprises in combination a pair of spaced guards surmounting a handle, a blade assembly reciprocable between 135 said spaced guards resting upon the lower guard of said pair of guards, a very obtuse projection on the upper side of said blade assembly and a cam roller mounted in the upper guard of said pair of guards having a wide angled cam 140 groove therein substantially complementary to said obtuse projection and adapted upon the rotation of said roller to reciprocate said blade assembly and to maintain the lower side of the blade assembly pressed against said lower guard 145 of said pair of guards by the action of the widely angled projection and cam groove.

OSCAR R. PETERSON.
